UNITED STATES PATENT OFFICE.

HARVEY J. LOUNSBURY, OF CHICAGO, ILLINOIS, ASSIGNOR TO WILLIAM H. MINER, OF CHAZY, NEW YORK.

CAR CONSTRUCTION.

1,303,341.

Specification of Letters Patent. Patented May 13, 1919.

Application filed July 1, 1918. Serial No. 242,848.

To all whom it may concern:

Be it known that I, HARVEY J. LOUNSBURY, a citizen of the United States, residing at Chicago, in the county of Cook and State 5 of Illinois, have invented a certain new and useful Improvement in Car Construction, of which the following is a full, clear, concise, and exact description, reference being had to the accompanying drawings, forming a 10 part of this specification.

This invention relates to improvements in car construction.

One object of the invention is to provide an unusually strong end frame construction 15 for railway cars and more especially for the rear ends of tenders that are subjected to heavy shocks.

More specifically, the object of the invention is to provide a cast end sill which is 20 securely united to the center sills and wherein the end sill is provided with an opening to accommodate the rear end of the draw bar and the front ends of a horizontal yoke and in addition is provided with integral upper 25 and lower horizontally extending shoulders adapted to form front stops for a shock absorbing mechanism.

In the drawings forming a part of this specification, Figure 1 is a top plan view of 30 the end of a tender underframe showing my improvements in connection therewith, the end portions of the end sill being broken away in order to prevent crowding of the drawing. Fig. 2 is a longitudinal, vertical, 35 sectional view, taken substantially on the line 2—2 of Fig. 1. And Figs. 3 and 4 are vertical, transverse, sectional views upon an enlarged scale, taken on the lines 3—3 and 4—4, respectively, of Fig. 2.

Referring to the drawings, 10—10 denote 40 heavy channel-shaped center sills of a tender underframe; A the improved cast end sill; B a combined stop and center bearing casting; C a draw bar; D a horizontal yoke; E 45 a front follower; F a rear follower; G—G twin-arranged friction gears; H a coupler key; J a detachable saddle plate for supporting the parts in position; and K a removable carry iron.

Referring to the combined stop and center bearing casting, the same is shown as provided with side walls 11—11 riveted to the center sills 10, a center bearing section 50 proper 12, horizontally extending, integrally formed upper and lower stops 13 and 14 vertically spaced to accommodate the rearward

movements of the yoke D therewithin, as clearly shown in Fig. 2, and suitable bracing flanges 15, 16, 17, 18, 19 and 20. In addition, said casting B is preferably provided with relatively short forwardly extended horizontal flanges 21—21 to form suitable guides for the horizontal yoke D in its movements.

The friction gears G are arranged one 65 above the other and are of a well known form and need not be specifically described. The same are confined between the arms of the yoke D and interposed between the followers E and F. The followers and gears 70 are supported by the saddle plate J which is preferably detachably secured to the lower flanges of the center sills by bolts 22.

The yoke D is arranged horizontally in a well known manner and is of unusually 75 heavy construction due to the high capacity of the shock absorbing mechanism. At their forward ends, the arms of the yoke D are enlarged as indicated at 23—23, the same being slotted to accommodate the coupler 80 key H which also passes through a suitable corresponding slot in the rear end of the draw bar.

The improved end sill casting A is shown as provided with an upper plate or wall 24 85 which extends over the center sills, and is riveted to the upper flanges thereof as indicated at 25. Said upper plate extends to each side of the center sill and is preferably tapered in a rearward direction as clearly 90 appears from Fig. 1. In addition, the end sill casting A is provided with rearwardly extended, vertical flanges 26—26 which fit against the inner faces of the center sills and are riveted to the center sills, as indicated 95 by the rivets 27. These flanges are preferably provided at their lower ends with in-turned narrow horizontal flanges 28—28 (see Fig. 3) which form suitable lower 100 guides for the horizontal yoke D. The end sill casting A extends from side to side of the car in a well known manner, the outermost portions thereof being broken away in Fig. 1, as hereinbefore referred to, and integrally formed with said end sill is a buffering block, as indicated at 29 in Fig. 2. At 105 its center, the end sill casting is provided with a rectangular opening designated by the reference 30 in Fig. 4, which opening is defined by an upper horizontal web 31, vertical side webs 32—32 and a lower horizontal web 33, the latter being preferably down-

wardly offset at its center, as indicated at 34 to easily accommodate the coupler butt. At its rear side, the end sill proper is formed with a transversely extending, vertical web 5 35 shown by the dotted lines in Fig. 1, and in elevation in Fig. 4, said vertical web 35 being cut away in alignment with the opening 30 to accommodate the movements of the draw bar butt and yoke, as will be understood. Said vertical web 35, between the center sills, forms horizontally extending vertical upper and lower stop shoulders 36 and 37 with which co-operates the front lower E. The end sill proper also involves another transversely extending vertical web 38 which goes from end to end and said vertical webs 35 and 38 may be suitably braced at desired intervals, as indicated by the dotted lines 39-39 in Fig. 1.

20 The carry iron K is of generally U-form with suitable flanges adapting the same to be bolted both horizontally and vertically to the end sill A, as indicated by the bolts 40 and 41.

25 As will be clear from the preceding description considered in connection with the drawings, the end sill is rigidly connected to the center sills by means of a comparatively large riveting area and in addition, it will be noted that the front stops 36 and 37 for the gear are exceedingly strong. Each of the front stops 36 and 37 is braced against a draft movement by a plurality of longitudinally extending sections of metal. The 30 upper shoulder 36 is braced in this manner by the upper plate 24, the upper wall 31 hereinbefore referred to and the upper portions of the vertical webs 32-32. The lower stop 37 is braced by the lower plate or wall 40 42 of the end sill casting and by the horizontal web 33 hereinbefore referred to. This construction is exceedingly strong and forms a protective housing for the inner end of the draw bar and the forward end of the yoke 45 as well as a support for said elements.

Although I have herein shown and de-

scribed what I now consider the preferred manner of carrying out the invention, the same is merely illustrative and I contemplate all changes and modifications coming 50 within the scope of the claims appended hereto.

I claim:

1. In car construction, the combination with the car center sills, of a cast end sill 55 having a pair of rearwardly extended flanges riveted to the inner sides of said center sills, said end sill having upper and lower, vertically spaced horizontally extending, integral, vertical webs forming transverse 60 shoulders on its inner side, each transverse shoulder extending from one of said flanges to the other, said shoulders being adapted to act as upper and lower front stops for a shock absorbing mechanism, each of said shoulder-forming webs being backed by a pair of horizontal webs.

2. As an article of manufacture, a cast end sill for railway cars, said end sill comprising a pair of transversely extending webs, a 70 top plate, a bottom plate, rearwardly extended securing flanges, said casting having a centrally disposed opening therein defined by upper and lower horizontal webs and vertical webs, said opening being adapted to 75 accommodate a draw bar butt and the front ends of a yoke.

3. In car construction, the combination with channel-shaped center sills, of a cast end sill extending from side to side of the 80 car, said cast end sill having a horizontal plate extended rearwardly over the center sills and riveted thereto, rearwardly extended flanges secured to the inner faces of the center sills, an integral buffering block, and 85 upper and lower transversely extending horizontal shoulders between the center sills.

In witness that I claim the foregoing I have hereunto subscribed my name this 13th day of June, 1918.

HARVEY J. LOUNSBURY.
